(57) **CLAIM**

The ornamental design for the ventilated seat pad for baby car seat or stroller, as shown and described.

DESCRIPTION

FIG. 1 is a perspective view of a first embodiment of a ventilated seat pad for baby car seat or stroller showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view of the ventilated seat pad for baby car seat or stroller of FIG. 1. A jagged thick broken tear away line is included to show the hidden surface of the front of the fan;

FIG. 9 is a perspective view of a second embodiment of the ventilated seat pad for baby car seat or stroller. A jagged thick broken tear away line is included to show the hidden surface of the front of the fan. The thin broken lines showing wiring features of the embodiment and the seatbelts representing the environment of use form no part of the claimed design; and,

FIG. 10 is a perspective view of a third embodiment of the ventilated seat pad for baby car seat or stroller showing a single hole seat belt pass through. A jagged thick broken tear away line is included to show the hidden surface of the front of the fan. The thin broken lines showing wiring features of the embodiment form no part of the claimed design.
